DES 564

Fig. 3.

Ms. 564

Samuel H. Sailor, of Philadelphia, Pa
Assignor to

James G. Abbott & Archibald Lawrence, of same place
Letters Patent No. 564 Dated May 10th 1853.

The schedule referred to in these Letters Patent and making part of the same

To all whom it may concern:

Be it known, that I, Samuel H. Sailor, of the city and County of Philadelphia, and State of Pennsylvania, have invented or produced a new and original design in Boot Stoves Called the

"New World"

and I do hereby declare that the following is a full, clear and exact description of the same; reference being had to the annexed drawings forming part of this specification, in which

Figure 1. is a side elevation of the stove.

Figure 2. is a front elevation of same, and

Figure 3. is a rear elevation.

In the symmetrical ornaments but one half the detail is given
Similar letters in the several figures, indicate the same part of the stove.

The side plates H, each contain the oven doors A, and D, and panel F; on one side, this latter is movable forming the feed door. On the upper part of this plate is the moulding I, arranged as seen in figure 1, and forming a cornice overhung by the top plate. Below the doors A and D, is the ogee moulding J, forming a continuation of the mouldings on the base plate.

The oven door A, is surrounded by a moulding B, composed of an ovolu a, cavetto b, and ogee c, forming a sunken panel C, which is ornamented in bas-relief by the foliage d, entwined around the elliptical figure C', the whole having the configuration and arrangement shown in figure 1. The door D is surrounded by the moulding E, similar to B, and is ornamented in bas-relief by the elliptical figure f, and foliage h, arranged and having the configuration set forth in figure 1. Above the door D, is the panel F, surrounded by a moulding G, similar to those around the doors A, and D, and ornamented with the elliptical figure g, as seen in figure 1.

The front feed opening is covered by the doors K, raised by the moulding I, formed of the ovolu l, and cavetto m, and surrounded by the bead n, bearing on the panels the inscription "Abbott & Lawrence", in raised capitals, arranged as shown in figure 2. Below these doors are the doors III, raised by the moulding IV, similar to I, and having in the panels the usual draft openings O.

On the front plate P, below the hearth Q, is the tablet R, surrounded by the moulding S, formed of the cavetto o, and ogee p, and bearing the inscription "N. World.", in raised capitals the whole arranged as seen in figure 2.

On the lower part of the front plate P, is the moulding T, similar to that on the bottom of the side plates, part of this moulding is movable forming the ash hole door U, on which is the inscription in raised capitals and numerals.

Patented 1853, the whole arranged as set forth in figure 2.

The base plate V, is surrounded by the moulding W, composed of the ogee t, and ovolu u, arranged as seen in figure 2.

The back plate X, is ornamented by the three rectangular panels

3

W. S. 566

Y, surrounded by the moulding Z, composed of the cavetto W and ogee X, combined as shown fully in figures 1, and 3.

The feet P' are of the form shown in figures 1 & 2, having their sides embellished with the sweeps a', scrolls b', and scales C, the front bearing the ellipsoidal projections d' and e', and otherwise ornamented as set forth in figures 1.

What I claim as my invention or production and desire to secure by Letters Patent, is

The configuration and arrangement of the ornaments in bas relief and mouldings on the front plate P, side plates H, back plate X, base plate V, oven doors A and D, door and panel F, feed doors K, draft doors M, and feet P', as fully set forth and described in this specification and annexed drawings, forming a new and ornamental design for the cook stove designated as the "New World".

In testimony whereof, I have hereunto signed my name before two subscribing witnesses.

Witnesses.
